GOLF PRACTICE DEVICE

Douglas M. Ford, 3 Hartman Place, Tuckahoe, N.Y.
10707, and Richard C. Schluter, 2420 Newton St.,
Vienna, Va. 22180

Filed Dec. 10, 1973, Ser. No. 423,230

Term of patent 14 years

Int. Cl. D16—02

U.S. Cl. D34—5 GC

FIG. 1

FIG. 2

FIG. 3

FIG. 4

FIG. 5

FIG. 1 is a top plan view of a golf practice device showing our new design;

FIG. 2 is a side elevational view thereof;

FIG. 3 is a bottom plan view thereof;

FIG. 4 is a rear elevational view thereof; and

FIG. 5 is a front elevational view thereof.

We claim:

The ornamental design for a golf practice device, as shown.
